[57] CLAIM

The ornamental design for a food mixer, as shown and described.

DESCRIPTION

FIG. 1 is a top front and left side perspective view of a food mixer showing my new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof; and

FIG. 7 is a bottom plan view thereof.

The broken line showing of the control buttons in FIGS. 1, 2, 3, 5 and 6 is illustrative of environmental structure only and forms no part of the claimed design.

FIG. 1

FIG. 2

FIG. 3

FIG. 4

FIG. 5

FIG. 6

FIG. 7
